UNITED STATES PATENT OFFICE

SAMUEL BUCHANAN McMASTER, OF COLUMBIA, SOUTH CAROLINA

FOOTBALL DOWN SIGNAL

Application filed February 27, 1931. Serial No. 518,820.

The object of this invention is to provide a simple device adapted to be carried by the head-linesman, and so constructed that he may readily manipulate it to indicate surely and positively to both the players and the spectators the number of downs that must be made before the ball is forfeited, as more fully hereinafter set forth.

Referring to the drawings annexed, Fig. 1 is a perspective view of a preferred form of my device;

Fig. 2 is a view partly in side elevation and partly in section;

Fig. 3 is a horizontal sectional view taken on the line 3—3 of Fig. 1;

Fig. 4 is a detailed perspective view showing particularly one of the latches; and

Fig. 5 is a perspective view showing the central box-like member with the slides removed.

Referring to the drawings annexed by reference characters, 6 designates the usual staff which has affixed to it near its upper end a hollow box-like central member 7, the upper portion of this staff 6 extending up through this member to form a top handle 8. This central member 7 is desirably rectangular in shape to provide four vertical faces. Around the lower half of the central body 7 is arranged a row of numerals 1, one numeral being on each face. The upper half of the central member is provided with another row of numerals 4, one digit being on each face.

Slidably mounted on the rectangular central member are three shields 9, 10 and 11, the two inner ones, 10 and 11 being adapted to telescope into the outer shield 9. These three shields are prevented from sliding off the ends of the central body 7 by means of a flange 12 at the upper end of the body and a similar flange 13 at the lower end of the body. These shields are mounted loosely on the body and within themselves so as to gravitate toward the lower flange 13 when released. The shield 10 is provided on each of its four sides with the numeral 2, and the shield 11 is provided with the numeral 3 on each of its four flat surfaces. Each of the shields is provided with an upstand-

ing hook-like finger-piece 14 to enable the head-linesman to raise the shields conveniently, and to hold the shields in raised position, as shown in Fig. 1, there is provided for each shield, on the top of the central member, a latch bar 15 pivoted at 16 and actuated by a spring 17 to normally swing into a notch 18 formed in the upstanding hook member 14. When it is desired to drop any one of the shields the latch bar 15 is swung to one side 60 out of engagement with the notch 18, and the shield is dropped by gravity until it rests on the lower flange 13. The shields can be dropped only one by one, the outer one 9 65 first, the intermediate one 10 next, and finally the inner one 11, which latter bears the numeral 3.

The manner of using the appliance is obvious to one familiar with the game of football. At the outset, before the ball is put 70 into play, the linesman raises all the shields, as shown in Fig. 1, leaving exposed on the four sides of the central member the numeral 1. He leaves the parts in this position until after the first down is made, and then 75 he drops the outer blank shield 9 so as to cover the numerals 1 and expose the numerals 2 on the next inner shield, 10; then after the second down is made he unlatches the shield 10 to permit it to drop into the non-use position within the previously dropped shield 9, 80 whereby the numerals 2 are covered from sight; then after the third down is made the linesman drops the shield 11 and thus exposes the numerals 4 on the top part of the 85 central body. It will be observed that by this simple apparatus the number of downs to be made by the team holding the ball will be plainly indicated not only to the players scattered over the field, but also to spectators in all directions, and that as the game progresses the head-linesman can readily shift the shield by simply releasing the 90 latches in succession.

In accordance with the provisions of the 95 patent statutes, I have herein described the principle of operation of my invention, together with the apparatus which I now consider to represent the best embodiments thereof, but I desire to have it understood 100

that the apparatus disclosed is only illustrative and that the invention can be carried out by other means. Also, while it is designed to use the various features and elements in the combinations and relations described, some of these may be altered and others omitted and some of the features of each modification may be embodied in the others without interfering with the more general results outlined, and the invention extends to such use. For instance, it will be obvious that any other form of latching device may be employed.

I claim:

- 15 1. A football down signal or marker embodying a staff, a central body member mounted on the staff, this body member being rectangular in horizontal section, and having a flange at its lower end and a flange at its upper end, the four faces of this central body member being provided around its lower portion with a row of numerals 1 and its upper portion being provided with a row of numerals 4, three rectangular shields slidably mounted on this central body member, the outer shield having its four outer faces blank and the two inner shields being provided respectively upon their four faces with the numerals 2 and the numerals 3, and means 20 for holding each of the three shields in their upper position to thus obscure all the numerals except the row of numerals 1 on the central member, whereby the shields may be dropped one by one as the game progresses.
- 25 2. A football down signal or marker embodying a staff, a central body member mounted thereon, a series of telescoping shields mounted on said central body member, and latch-means for permitting the shields to be dropped or lowered one by one, said body member and shields being provided with numerals to indicate the number of downs to be made before losing the ball.
- 30 3. A football downmarker or signal embodying a staff, a central body member mounted thereon, provided at its lower part with a row of similar numerals and at its upper part or zone with another row of different numerals, a plurality of shields mounted to telescope up and down on said member, the outer shield being unprovided with numerals and the inner shields each being provided with a horizontal row of numerals, and means for holding all the shields in an up position to thereby expose 35 only the numerals on the lower part of the main central member.

In testimony whereof I hereunto affix my signature.

60 SAMUEL BUCHANAN McMASTER.
